Stray Light Optical Technologies, Photograph of Light Emitting Plasma Streetlight, Disclosed before Nov. 10, 2009, one page.

Primary Examiner — Susan M Lee*Assistant Examiner* — Linda Brooks(74) *Attorney, Agent, or Firm* — Baker & Daniels LLP(57) **CLAIM**

We claim the ornamental design for the lighting apparatus, as shown and described.

DESCRIPTION

FIG. 1 is a bottom perspective view of a lighting apparatus of the present invention;

FIG. 2 is a top perspective view of a lighting apparatus of FIG. 1;

FIG. 3 shows a bottom view of the lighting apparatus of FIGS. 1 and 2;

FIG. 4 shows a top view of the lighting apparatus of FIGS. 1 and 2;

FIG. 5 shows a left side view of the lighting apparatus of FIGS. 1 and 2;

FIG. 6 shows a right side view of the lighting apparatus of FIGS. 1 and 2;

FIG. 7 shows a front view of the lighting apparatus of FIGS. 1 and 2;

FIG. 8 shows a rear view of the lighting apparatus of FIGS. 1 and 2; and,

FIG. 9 is a top perspective view of the lighting apparatus of FIGS. 1 and 2, with an orientation of the components being changed.
